(57) **CLAIM**

The ornamental design for an apparatus for pet hair removal as shown and described.

DESCRIPTION

FIG. 1 is a front, top, first side isometric perspective view of an apparatus for pet hair removal in accordance with my design;

FIG. 2 is a rear, top, first side isometric perspective thereof; FIG. 3 is a first side elevation view thereof;

FIG. 4 is a second side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines illustrate portions of the apparatus for pet hair removal which form no part of the claimed design.

The claimed design is shown with a symbolic break in its length. The appearance of any portion of the apparatus for pet hair removal between the break lines forms no part of the claimed design.

The claimed design shows a contrast of materials by using line shading in one area-and stippling in another.
